UNITED STATES PATENT OFFICE.

GEORGE E. PRENTICE, OF NEW BRITAIN, CONNECTICUT, ASSIGNOR TO TREO COMPANY, INC., A CORPORATION OF NEW YORK.

BUCKLE.

Application filed March 10, 1923. Serial No. 624,129.

To all whom it may concern:

Be it known that I, GEORGE E. PRENTICE, a citizen of the United States, residing at New Britain, in the county of Hartford 5 and State of Connecticut, have invented certain new and useful Improvements in Buckles, of which the following is a full, clear, and exact description.

My invention relates to a buckle for adjustably connecting together two bands or a band to a garment, and particularly to a buckle having a sliding bar in a frame with the free end of the adjustable band passed into the frame at the further side of the bar, 15 then over the bar, and then through the frame on the nearer side of the bar, so that any pull on the adjustable band will shift the bar automatically in a direction to clamp the free end of the band between it and the 20 frame. In prior buckles of this type, the bars have usually been made by stamping the same from sheet metal, and the edges of these bars over which the bands pass were frequently rough and sharp. The result 25 has been that the bands were soon worn and frayed. If any slack occurred at times in the adjustable band, the locking bar would frequently slide on the frame sufficiently to loosen the locked end of the band and result 30 in an undesired loosening of the band or connection. The adjustable band exerts a turning torque upon the bar or sliding locking element, which torque tends to damage or break the sliding connection between 35 the bar or element and the frame.

An object of the invention is to provide an improved buckle which may be made entirely by stamping the parts thereof from sheet metal; and then, if necessary, bending 40 the same into the desired shape; with which there will be no possibility of damage to the bands; in which damage to the buckle frame or locking bar due to turning torques produced on the bar by the pull on the adjustable band will be avoided; with which 45 accidental loosening or effective lengthening of the adjustable band will be largely or entirely prevented; and which is thin, light in weight, simple, strong and durable in 50 construction, attractive in appearance and inexpensive. Other objects and advantages will be apparent from the following description of an embodiment of the invention and the novel features will be particularly pointed 55 out hereinafter in claims.

In the accompanying drawing:

Fig. 1 is an elevation of an adjustable garter strap which has included therein a buckle constructed in accordance with the invention, 60

Fig. 2 is a longitudinal section through a portion of the same including the buckle, taken substantially along the line 2—2 of Fig. 1,

Fig. 3 is a perspective of the sliding bar 65 or locking element.

Fig. 4 is a transverse section through the buckle taken substantially along the line 4—4 of Fig. 1, and

Fig. 5 is a plan of the initial stamping 70 from which the sliding bar or locking element is formed.

In the illustrated embodiment of the invention, the buckle frame 1, with a large aperture 2 therein, may be stamped from 75 suitable sheet material, or formed in any other suitable manner. A blank 3 of substantially the shape shown in Fig. 5 with aligned notches in the end edges, is stamped from suitable sheet metal. This stamping 80 3 is folded upon itself along parallel lines into a tubular form that is substantially rectangular in cross-section. One edge portion 4 of the stamping, after forming one side edge of the tubular bar, is bent outwardly at substantially right angles thereto so as to form a flange 5 which extends parallel to the two faces of the bar and in slightly spaced relation to one of the faces thereof. This spacing is preferably slightly less 85 than the thickness of the band to be used in the buckle.

The folding of the stamping which preferably is along the side edges of the notches, will produce a tubular locking bar or element in which the notches will form slits in the ends thereof. In effect, this is the equivalent of having the opposite face of the sliding bar or element extended so as to provide a pair of spaced tongues at each 100 end. The sliding bar or locking element is disposed across the aperture 2 of the frame 1 with the spaced tongues 6 at each end overlying opposite faces of the frame along the aperture, so as to guide the bar for sliding movement on the frame across the aperture, and at the same time retain the bar against removal from the frame. When the bar is at one limit of its sliding movement the flange 5 will overlie a portion of 105 110

the frame along the aperture 2, in slightly spaced relation therewith.

A strap 7 is passed through the aperture 2 and around an edge of the frame, and 5 stitched or otherwise secured upon itself, as at 8, so as to form a permanent connection between the same and the buckle. An adjustable strap or band 9 which, by way of illustration, may carry a suitable garter 10 fastening device 10 at one end thereof, is passed through the aperture in the frame between the sliding bar and the strap 7, then around the sliding bar and back through the aperture in the buckle frame 15 upon the other or nearer side of the bar. When a pull is exerted upon the strap 8 it will be transmitted to the sliding bar in such a manner as to pull the bar in the direction of pull upon the strap, and clamp the 20 free end of the strap 9 between the sliding bar and the buckle frame.

The flange 5 will wedge the free or clamped end of the adjustable band between it and the face of the buckle frame, so that 25 if any slack occurs in the adjustable band, there will be sufficient friction between the bar, the band, and the buckle frame to prevent accidental movement of the sliding bar in a direction to release the free end of the 30 adjustable band. The flange 5, by its engagement with the face of the buckle frame, through the interposed free end of the adjustable band, will resist any rotary movement of the sliding bar which would tend 35 to twist the tongues 6 in a manner to release the bar from the frame or otherwise damage it. If one desires to lengthen or shorten the adjustable band it is merely necessary first to slacken it so that the sliding bar may be shifted to release the free end 40 thereof, after which the band may be adjusted to the desired length. Thereafter, when a pull is exerted upon the adjustable band or strap, it will be transmitted to the 45 sliding bar and shift the latter in a direction to clamp the free end of the band or strap to the buckle frame.

It will be observed that the buckle frame and sliding bar may both be produced entirely by metal die stamping and bending operations, which enables their production in quantities at an exceptionally low cost. The buckle also will not readily release or loosen the strap when slack occurs in the 55 adjustable band, and since the turning torque is taken from the guiding flanges of the sliding bar, the buckle will be exceptionally durable. The buckle frame may be very short, and since it may be formed of sheet metal, it will be thin, inconspicuous and light in weight. The parts of the buckle

being of metal may be plated or given any desired style of finish.

It will be obvious that various changes in the details, shapes and arrangement of 65 parts herein described and illustrated for the purpose of explaining the nature of the invention, may be made by those skilled in the art within the principle and scope of the invention as expressed in the appended 70 claims.

I claim:

1. A buckle comprising an apertured frame, and a locking bar of sheet metal which has been bent upon itself into tubular 75 form, extending across the aperture between opposite sides of the frame, both ends of the bar having longitudinal extensions overlying both faces of said opposite sides of the frame so as to guide the bar for sliding movement on the frame across the aperture and retain it against removal from the frame.

2. A buckle comprising an apertured frame, a sheet metal tubular locking bar 85 extending across the aperture between opposite sides of the frame, both ends of the bar having longitudinal extensions overlying both faces of said opposite sides of the frame so as to guide the bar for sliding movement on the frame across the aperture and retain it against removal from the frame, the bar having a flange along one edge which, when the bar is at one limit of 90 its movement, slightly overlies one face of the frame.

3. A buckle comprising an apertured frame, and a strip of sheet metal bent upon itself into tubular form and disposed endwise across the aperture between opposite 100 sides of the frame, the ends of the strip having tongues which cooperate with the frame sides to retain the strip on the frame and allow it to slide across the aperture, one edge portion of the strip after forming 105 one side edge of the sliding form extending toward the adjacent edge of the frame in a plane spaced to the rear of the rear face of the frame.

4. A buckle comprising an apertured frame, and a tubular bar carried by the frame across the aperture thereof for sliding movement across the aperture laterally of itself, said bar having a flange along an edge which extends toward the adjacent 115 edge of the aperture in a plane spaced from a face of the frame and exteriorly of the plane of the aperture.

In witness whereof, I hereunto subscribe my signature.

GEORGE E. PRENTICE.
